RADIO RECEIVING SYSTEM

Paul O. Farnham, Boonton, N. J., assignor to
 Radio Frequency Laboratories, Incorporated,
 Boonton, N. J., a corporation of New Jersey

Application November 4, 1932, Serial No. 641,281

10 Claims. (Cl. 250—20)

This invention relates to radio receiving systems of the automatic gain control type, and particularly to methods of and circuit arrangement for securing a desirably flat gain control 5 characteristic in receivers using vacuum tubes with filamentary cathodes.

To minimize the effects of fading and/or to avoid manual changes in sensitivity as the receiver is tuned over the frequency band, it is desirable to reduce the amplifier gain automatically with increases in the radio voltage input but this automatic control should not come into action until the receiver input rises to that critical value which, with maximum amplifier gain, 10 will provide the maximum desired audio output at the loud speaker. The automatic control of the receiver sensitivity is obtained, in general, by rectifying the output of a radio frequency amplifier to obtain a direct current voltage 15 which is returned to the amplifier as a bias or gain control voltage. More particularly, the preferred types of gain control systems have included rectifier systems in which no rectification took place until the radio amplifier output 20 increased to a certain critical level, but which developed a rectified voltage that increased rapidly with increases in radio output above the critical level. Systems of this type have usually involved the connection of the cathodes of some 25 tubes of the receiver to a point of direct current potential different from that of the cathodes of other tubes.

Although this condition is easily realized in the case of tubes of the separate heater type, it 30 presents the decided disadvantage that separate sources of filament current supply must be used for the groups of filament type tubes which are to be operated with different direct current potentials on the cathodes.

An object of the present invention is to provide 35 a gain control system for receivers of the filamentary cathode type, which system gives a delayed control action without the use of separate filament supply sources for different groups 40 of tubes. Another object is to provide a radio receiver using filament type tubes, and which includes simple and efficient circuit arrangements for delaying a gain control system to obtain 45 a desirable gain radio input characteristic. A further object of the invention is to provide, in receivers of the automatic gain control type, a rectifier system including diode detection of the modulated radio signal and a delayed or 50 biased diode rectification for the development of a gain control bias.

These and other objects and advantages of the invention will be apparent from the accompanying drawing in which the single figure is a fragmentary circuit diagram of an embodiment 55 of the invention.

In the drawing, the reference numeral 1 identifies a radio frequency amplifier deriving its carrier wave input from an antenna or collector structure 2, and including a plurality of amplifier tubes 3 between the antenna and an output 65 coil 4 which is coupled to the tuned input circuit 5 of the detector-automatic control stage. The several tubes of the amplifier 1 and the coupling between the tubes may be of any desired or appropriate type and, in the drawing, only those elements of the tubes which are directly related to the invention have been illustrated.

The detector-control stage preferably includes only a single tube, which may be of the screen grid construction known as type 232, but it will 75 be apparent that the novel method of operation may be obtained by the use of separate detector and control tubes.

One terminal of the tuned circuit 5 is grounded and the opposite terminal is connected, through 80 condensers 6, 7, 8, respectively, to the inner grid G₁, the outer grid G₂ and the plate P of the tetrode 9. Each of these cold electrodes cooperates with the filamentary cathode F to function as a diode rectifier. The radio frequency voltage which is 85 impressed between grid G₁ and the cathode is rectified in the audio frequency output circuit formed by connecting resistance 10 between the grid and the grounded or negative terminal of the cathode F. The resulting audio frequency volt- 90 age E₀ may be taken off between ground and the terminal 11 which is connected to grid G₁. This audio output will usually be further amplified before it reaches the loud speaker or other reproducer, not shown.

The plate P cooperates with the filament or cathode F to form the elements of the diode rectifier of the gain control system. The output resistance 12 is connected between the plate and a tap 13 on the C-battery 14, the direct current 100 potential E₁ thus established on the plate being negative with respect to the grounded terminal of filament F. The plate terminal of the output resistance 12 is connected, through a filter comprising resistance 15 and condenser 16, to the lead 105 17 that extends to the inductances 18, and thence to the grids G of tubes 3.

The low potential terminals of inductances 18 are grounded, for radio frequency potentials, by condensers 19, and the lead 17 includes resistances 20 which prevent any coupling of the tube 110 input circuits through the gain control system.

The filamentary cathodes F of all tubes are connected in parallel across the filament supply or A-battery 21. A B-battery 22 is provided for 115 energizing the plate and screen grid circuits, not shown, of the amplifier tubes.

The circuit elements, as so far described, comprise an automatic gain control system which is operative, but which cannot provide a gain con- 120

trol characteristic having the desired flat top and a relatively sharp cutoff at the critical value of receiver input. When the tap 13 is initially set to establish a negative bias voltage E_1 on the amplifiers 3 which is appropriate for the maximum amplifier gain, the same negative bias is applied to the plate P of the detector-control tube 9. From the known operation of gain-control systems which include a biased or delayed action diode rectifier, it is apparent that no rectification will take place until the peak radio input voltage E exceeds the delay bias voltage E_1 . In general, however, an adjustment of voltage E_1 for satisfactory amplification in the radio frequency amplifier does not provide a sufficiently high negative or delay bias on the diode rectifier PF to obtain a satisfactory control characteristic. On the other hand, an adjustment of the bias voltage E_1 to provide a satisfactory delay bias on the rectifier will place such a high negative bias, of the order of from 10 to 20 volts, on the amplifier tubes 3 that the gain of the radio amplifier will be seriously reduced.

In accordance with this invention, the action of the negative or delay bias voltage E_1 on the gain control rectifier PF may be effectively increased to prevent rectification until the radio input voltage E on the diode rises to much higher values than that corresponding to the actual bias voltage E_1 . This effect is obtained by means of the grid G_2 which cooperates with the filament F to form a diode rectifier that is operated under a negative or delay bias applied to the grid G_2 through the resistor 23 and the C-battery 14. It has been demonstrated that as the delay bias voltage E_2 is progressively increased to place a greater negative bias on this diode, rectification in the PF diode circuit does not occur until the radio voltage E reaches correspondingly higher values. The effective delay bias voltage on the gain control rectifier PF may therefore be increased to any appropriate value in excess of the bias E_1 which is applied both to the plate of tube 9 and to the grids of the amplifier tubes 3.

It is therefore possible to choose an initial bias voltage E_1 which is appropriate for maximum gain in the radio amplifier and which, in combination with the delay bias E_2 on the grid G_2 , postpones the initiation of the action of the automatic gain control system until the receiver input reaches the critical value which, with maximum gain, will deliver the desired maximum audio frequency output at the loud speaker. With increasing receiver input voltages above this critical value, the gain control diode passes a direct current voltage which increases at a relatively rapid rate to reduce the amplifier gain and thereby hold the receiver output at a substantially constant level.

The following values of the more important constants of the rectifier circuit were found suitable in one particular case:—

Resistor 10=100,000 ohms
 Resistor 12=1 megohm
 Resistor 15=½ megohm
 Resistor 23=2 megohms
 Condenser 6=100 micromicrofarads
 Condenser 7, 8=0.01 microfarad
 E_1 =3 volts
 E_2 =12 volts
 Tube 9=type 232

While the invention is particularly useful in connection with tubes having filamentary cathodes, it will be apparent that the same general method of increasing the effect of a delay bias

voltage may be employed with tubes of the separate heater type.

I claim:

1. In a radio receiver, the combination with a vacuum tube having a cathode and an anode comprising the elements of a diode having the inherent characteristic of rectifying an impressed alternating current voltage when the peak alternating voltage exceeds that critical value which is the direct current potential between the said diode elements, an input circuit for impressing radio voltages between said elements, and an output circuit, of means preventing rectification by said diode until the peak radio voltage impressed thereon rises to a predetermined value differing from and greater than said critical value by a voltage increment of substantial magnitude. 80
2. The invention as set forth in claim 1, wherein said rectification preventing means comprises a third tube element, circuit elements cooperating with said third element and cathode to form a second diode rectifier, and bias means for impressing a direct current potential between said third element and cathode. 85
3. In a radio receiver, the combination with a vacuum tube having a cathode and an anode comprising the elements of a diode rectifier, of an input circuit for impressing radio voltages on said tube, an output circuit, means applying a direct current potential between anode and cathode to bias the diode rectifier to postpone rectification until the peak radio voltage impressed on said rectifier exceeds the applied bias voltage, and means additional to the bias voltage applied between anode and cathode for controlling that value of the impressed radio voltage above which rectification will take place. 90
4. In a radio receiver, the combination with a vacuum tube having a cathode and at least two anodes, one of said anodes being located between said cathode and the other anode, of input circuit means impressing radio voltages between each anode and the cathode, an output circuit between each anode and the cathode, and delay means preventing the development of a rectified voltage in the output circuit of the outer anode until the radio voltage impressed upon the input circuit thereof exceeds a predetermined value, said delay means including a source of direct current voltage impressing upon the inner anode 110 a bias voltage that is negative with respect to the cathode. 115
5. In a radio receiver, the combination with a vacuum tube having a cathode and at least two anodes, one of said anodes being located between said cathode and said other anode, each of said anodes together with the cathode comprising the elements of diode rectifiers, of an input circuit for impressing radio voltages on each of said diode rectifiers, an output circuit, and means applying a direct current potential between the inner anode and cathode, whereby rectification between the cathode and the outer of said anodes is postponed until the impressed radio voltage exceeds a predetermined value. 120
6. The invention as set forth in claim 3, wherein said independent means comprises a tube element between the anode and cathode, and circuit elements cooperating with said tube element and cathode to form a diode rectifier, said circuit elements including means applying to the said tube element a direct current potential which is negative with respect to the cathode and different from the negative potential on the anode. 130
7. In a radio receiver, the combination with a 150

- radio frequency amplifier, and a rectifier working out of said amplifier, of means for biasing said amplifier to control the gain thereof, said means including said rectifier, a single source of direct current potential for initially applying a negative bias voltage to said amplifier and rectifier, and means preventing rectification by said rectifier until the peak radio input on said rectifier exceeds a value which is substantially greater than that of the negative bias voltage applied to the rectifier. 80
8. In a radio receiver, a radio frequency amplifier tube having a control grid and cathode, a diode rectifier having an input circuit coupled to the amplifier output circuit, said amplifier tube and diode rectifier having their cathodes connected to each other and maintained at the same direct current potential, a resistance and a source of direct current potential connected between the amplifier cathode and control grid to apply a negative bias to said amplifier tube, a rectifier output circuit including said resistance and said current source, whereby a negative bias is applied to the rectifier anode, and means preventing rectification by said rectifier until the peak radio voltage impressed thereon rises to a critical value substantially greater than that of the negative bias on said rectifier. 90
9. The invention as set forth in claim 8, wherein in said last means comprises a third tube electrode 95
- between the rectifier anode and cathode, a diode input circuit coupled to the amplifier output circuit and connected between the said electrode and the cathode, and means for applying to said electrode a direct current potential different from that of said anode. 100
10. In a radio receiver employing filament type tubes, the combination with an amplifier tube having a control grid and filament; an output circuit for said tube; a detector-control stage including a tube having a filamentary cathode, a detector anode, a rectifier anode and a grid between said cathode and rectifier anode; input circuit means coupled to said amplifier output circuit to impress a radio voltage between said cathode and each of the other tube elements; and an audio output circuit for the cathode-detector anode rectifier; of a common source of current for the amplifier filament and detector-control tube cathode, bias means for the control grid of said amplifier tube and including a direct current source in series with a resistance, a rectifier output circuit including said series current source and resistance, whereby a delay bias is established on said rectifier anode, and a diode output circuit for said grid and cathode, said diode output circuit including a direct current source impressing on the grid-cathode diode a negative bias in excess of the delay bias on said rectifier anode. 105
